DESIGN FOR A DRIVE HANDLE FOR TOOLS

Arthur L. Cornwell, Wellsville, N. Y.

Application September 28, 1935, Serial No. 58,752

Term of patent 14 years

To all whom it may concern:

Be it known that I, Arthur L. Cornwell, a citizen of the United States, residing in Wellsville, in the county of Allegany and State of New York, have invented a new, original, and ornamental Design for a Drive Handle for Tools, of which the following is a specification, reference being had to the accompanying drawing, forming a part thereof, in which,—

Fig. 1 is a face elevation of a handle showing my design,

Fig. 2 is a side elevation thereof.

The dominating features of my design reside in two symmetrical arm portions with thickened ends and a closed raised portion centrally disposed on the outer face of the handle.

I claim:

The ornamental design for a drive handle for tools substantially as shown and described.

In testimony whereof, I have affixed my signature hereto.

ARTHUR L. CORNWELL.
